APPARATUS FOR CONTROLLING THE FLOODING OF LIQUID TANKS OR COMPARTMENTS

Marvin H. Grove, Piedmont, Calif.

Application February 6, 1942, Serial No. 429,732

4 Claims. (Cl. 114—198)

This invention relates generally to apparatus for controlling the flooding of tanks or compartments, particularly the compartments of ships.

In connection with war ships and other marine craft, it is customary to provide compartments within the ship hull, together with means for flooding the compartment with water. Flooding may be necessary to trim the ship in the event of an emergency, as for example the rupture of one or more other compartments, or possibly for the purpose of extinguishing fires. It is desirable that the flooding be capable of remote control, and the main control valve should be such as to enable both remote opening and closing to secure the degree of flooding desired, and permit pumping out water from a flooded compartment.

The present invention has for its object the production of a simple flood control equipment of the above character which will make possible use of large sized valves without requiring application of appreciable operating power.

Another object of the invention is to provide equipment of the above character which will operate satisfactorily irrespective of the amount of water in the tank or compartment.

Additional objects of the invention will appear from the following description in which the preferred embodiment has been set forth in detail in conjunction with the accompanying drawings.

Referring to the drawings:

Figure 1 is a side elevational view illustrating my apparatus in conjunction with a ship compartment; and

Figure 2 is an enlarged cross sectional detail showing a valve of the expandable tube type together with a control valve for the same.

Referring first to Figure 1, the apparatus illustrated consists generally of a main valve 10 in conjunction with a control valve 11. In addition, there is an auxiliary reservoir or trap 12 which serves a purpose to be presently described. All of these parts are disposed in a ship compartment 13 at a substantial depth below the exterior water level 14.

The inlet side of the main valve 10 is connected to inlet pipe 16 which in turn communicates through the bottom of the hull. Pipe 17 serves to deliver the water passing through the valve directly to the lower part of the compartment. In some instances pipe 16 may connect to pumping equipment, instead of taking water directly from the exterior of the hull.

Figure 2 shows a suitable main valve 10 of the expandable tube type. Such a valve is disclosed and claimed in Bryant application 460,091, filed September 29, 1942. It includes a body having inflow and outflow passages 21 and 22 which communicate with the pipes 16 and 17. Within the body there is a barrier 23, which is surround-

ed by a flexible tube 24 formed of suitable material such as resilient rubber. Slotted sleeves 26 and 27 extend from the opposite sides of the barrier 23 and serve to prevent inward collapsing of the tube 24 in addition to retaining the barrier in place. The ends of the tube 24 are sealed with respect to the body as illustrated. About the tube there is a closed annular chamber 28 adapted to receive liquid under pressure whereby the tube can be either closed upon the periphery of the barrier 23, or permitted to expand to open position when pressure in chamber 28 is reduced to atmospheric.

Fluid pressure for introduction into chamber 28 is preferably taken from the inflow side of the valve through the pipe 31. This pipe connects to the control valve 11, and the control valve also connects with chamber 28 through pipe 32. Another venting pipe 33 leads from control valve 11 and serves to carry away liquid vented from chamber 28, as will be presently explained. The control valve has two operating positions. In one position pipes 31 and 32 are placed in communication so that liquid from the inlet side of the valve is applied to chamber 28 to maintain the tube 24 closed upon barrier 23. In the other operating position, communication between pipes 31 and 32 is interrupted, and pipe 32 is placed in communication with pipe 33 to cause venting of liquid from chamber 28, thus permitting the tube 24 to expand to open position whereby water can flow through pipe 16, valve 10, and the discharge pipe 17 to enter the compartment.

The control valve may be any type capable of operation from a remote point. For example, it may be a simple mechanical valve connected for mechanical operation from a remote point, as by means of a flexible shaft, pull cables or the like. The type of control valve illustrated is of the hydraulic pressure operated type. Briefly, it consists of a body 36 connected to the pipes 31, 32 and 33, and provided with two valve seats 37 and 38. A small valve member 39 cooperates with the valve seats 37 and 38, and when closed upon seat 37, pipes 32 and 33 are placed in communication, and when engaged upon seat 38, pipe 31 communicates with pipe 32. An operating stem 41 connects with valve 39, and extends through the packing gland 42. Stem 41 connects with an operating rod 43 which in turn engages a diaphragm plate 44. This plate engages the fluid operated diaphragm 46, and is urged against the diaphragm by the compression spring 47. The closed fluid chamber 48 on one side of the diaphragm 46 is connected to the pipe or tube 49 which leads to a remote operating point, where suitable means is provided to apply oil or other liquid under pressure. When pressure is applied to pipe 49, the diaphragm 46 is flexed to move the valve 39 against the seat 37.
